UNITED STATES PATENT OFFICE

2,437,241

TOY GYMNASIUM FOR BABY CRIBS

Leslie H. Burlin, Valparaiso, Ind., assignor to
 Milton L. Sturm, Evanston, Ill., doing business
 as Milton Sturm & Company, Chicago, Ill.

Application December 10, 1945, Serial No. 633,973

7 Claims. (Cl. 272—61)

1

This invention relates to amusement and exercising devices for use by very small children, particularly by infants lying in a crib.

It is one of the objects of the present invention to provide a toy of the type which may be stretched across a baby's crib or play pen and which toy may be swung from one position to alternate position in response to a tug or pull on the toy by the baby. The toy is provided with two handles so arranged that a pull on one handle causes the toy to swing in one direction and a pull on the other handle causes the toy to swing in the opposite position.

It is one of the objects of the present invention to provide a toy of the above mentioned character with an animated figure which swings from one position to an alternate position in response to the tugs of the infant on the respective handles. As the toy is swung by the infant from one position to the other the animated figure on the toy also pivots to an alternate position. This constitutes a source of attraction and amusement to the infant and thereby repeatedly attracts the child to operate the toy. This not only keeps the child amused, and therefore happy, but also results in exercising of the child with consequent benefits.

The attainment of the above and further objects of the present invention will be apparent from the following specification taken in conjunction with the accompanying drawing forming a part thereof.

In the drawing:

Figure 1 is a front view of the toy of the present invention;

Figure 2 is an enlarged view of one of the handles of the toy; and

Figure 3 is a sectional view taken along the line 3—3 of Figure 1.

In the drawing the reference numerals 1 and 2 indicate a pair of end members. The end member 1 comprises a cylindrical body portion 3 having a knob 4 projecting from the top and a similar knob 5 projecting from the bottom. The body portion 3 is provided with a pair of holes 6—7 drilled into but not through the body portion. The holes 6—7 are parallel and one end of a rail member 8 is permanently secured in the hole 6. The rail member 8 is substantially circular in cross section but is provided with a longitudinal groove 9 in its lower surface. Another rail member 10, similar to the member 8, has one end permanently secured in the hole 7 and is provided with a longitudinal groove 11 in its upper surface. The opposite ends of the rail 55

2

members 8 and 10 are secured in the end member 2 which is a duplicate of the end member 1. A plurality of marbles 12 is mounted between the grooves 9 and 11 so as to be freely movable longitudinally of the rail members in either direction as the device is tilted. The grooves 9 and 11 are deep enough so that the marbles can not come out.

An upright member 13, centrally disposed, is provided with parallel apertures 14—15, through which the rail members 8 and 10 pass. The member 13 has a knob 16 projecting from its top and a knob 17 projecting from its bottom. The knob 16 is provided with a groove 18 arranged parallel to the apertures 14 and 15. An animated figure 19 is mounted in the groove 18 and is secured in pivotal relation thereto by means of a pin 20 driven into the knob 16 and through the portion of the animated figure projecting into the groove 18.

The figure 19 is provided with a pair of apertures 21—22 spaced slightly higher than the knob 16 and on either side thereof. A tape or string 23 has its central portion permanently secured to the lower portion of the animated figure by being passed through the aperture 21 twice, then over to the aperture 23 and through it twice. It will be obvious that the tape or string 23 would be operative to a certain extent if it were passed through the apertures 21 and 22 only once. It is also possible to use two separate tapes and tie one end of each to one of the apertures 21 and 22. However, I prefer the structure illustrated because no knots are visible with the single tape and the double passing through the apertures 21 and 22 provides a more positive actuation of the animated figure.

One end of the tape 23 is threaded through a plurality of bead like members 24 one of which is preferably elongated to serve as a handle which the infant may grab and hold. The end of the tape is then passed through an aperture 25 in the knob 5 and is tied into a knot. The aperture 25 is relatively large on the right hand side of the knob 5 as seen in Figure 1, but is of reduced diameter on the left side. After the knot is tied it is pulled into the wide portion of the aperture 25 but cannot pass through the small portion. The opposite end of the tape 23 is secured to the knob 17 in the same manner.

A teething ring 27 is secured to the knob 17 by means of a tape 28. One or more bead like members 29 may be mounted on the tape 28 to increase its attractiveness to an infant.

A securing member 30 has a tape 31 threaded

through a pair of apertures 32 adjacent its opposite ends and then both ends of the tape are passed through an aperture 33 in the knob 4. The aperture 33 has one end of large diameter to receive the knot by which the ends of the tape 31 are tied together and has one end of reduced diameter to prevent the knot passing through. A second securing member 34 is secured to the knob 35 by the tape 36 tied in the same manner. In order to secure the device to a crib, play pen or similar supporting structure the securing member 30 is wrapped around a member 37 comprising part of the supporting structure and is then tucked under the tape 31 to form a loop 38 embracing the member 37, as shown in Figure 1. 15 Tension on the tape 31 tightens the loop 38 until the securing member 30 and the support member 37 are in juxtaposition.

The operation of the device is obvious from the foregoing description. When the securing members 30 and 34 are secured to the supporting members 37 the handles 34 should be within grasping distance of the infant. A slight tug or pull on either handle will cause the corresponding end of the animated figure to move downwardly. Continued tension on the same handle will tilt the device and cause the marbles 12 to roll down the rails. A tug on the other handle 34 will reverse the entire sequence of events.

Although I have described a preferred embodiment of my invention in considerable detail it will be understood that the description thereof is illustrative, rather than restrictive, as many details may be modified or changed without departing from the spirit or scope of the invention. Accordingly, I do not desire to be restricted to the exact construction described, except as limited by the appended claims.

I claim:

1. In a toy gymnasium and exerciser for cribs and of the type which is to be supported in a manner permitting free movement thereof a pair of end members and a pair of parallel rail members secured therebetween, said rail members having oppositely disposed longitudinally extending grooves, a plurality of marbles permanently secured between said grooves, said marbles being free to roll in either direction as the device is tilted, an upright member through which said rail members extend, a groove in the upper portion of said upright member, an animated figure pivotally mounted in said groove, a pair of apertures in said animated figure on opposite sides of and slightly higher than the point at which said animated figure is pivoted, a tape passing through both of said apertures, the opposite ends of said tape being secured to said end members, and a pair of handles secured to the tape, one handle being on either side of said animated figure whereby said animated figure may be moved on its pivot by a pull on either handle and force on said handle will tilt said rails to cause said marbles to roll from one side to the other.

2. In a combination toy and exerciser and of the type which is to be supported in a manner permitting free movement thereof, a pair of parallel rails having a plurality of freely movable

marbles permanently secured therebetween, a fixed member projecting above said rails, an animated figure pivotally secured to said projecting member, and a tape secured to said figure, said tape being operable to move said figure about its pivot and force on said tape will tilt said rails to cause said marbles to roll from one side to the other.

3. In a combination toy and exerciser, a pair of parallel rails having a plurality of freely movable marbles permanently retained therebetween, flexible means for securing said rails to a crib while permitting their free movement, an upright member fixed to said rails, an animated figure pivotally secured to said upright member, and a pair of handles operatively connected to said animated figure, whereby a pull exerted on either handle will cause said figure to move about its pivot and continued force on said handle will tilt said rails to cause said marbles to roll from one side to the other.

4. In a combination toy and exerciser, a rail member, means for detachably securing said rail member to a crib, an animated figure pivotally secured to said rail member, cords secured to said figure on opposite sides of the pivot, handles secured to said cords, said handles being operative to move said figure around its pivot point.

5. In a combination toy and exerciser, a figure pivotally secured to a member constituting a support therefor, said figure having an aperture on each side of its pivot point in a plane above said pivot point, and a tape secured to each of said apertures whereby said figure may be moved in either direction around said pivot point.

6. In a combination toy and exerciser, a rigid member, a pair of tapes secured at the opposite end of said rigid member for securing said rigid member to a crib in horizontal position, a pivoted member secured to said rigid member intermediate its ends, and means secured to said pivoted member operative to move said pivoted member on its pivot and to tilt said rigid member from said horizontal position.

7. In a combination toy and exerciser, a rigid member, a pair of tapes secured at the opposite ends of said rigid member for securing it to a crib in horizontal position, a pivoted member secured medially of said rigid member, and a pair of tapes secured to said pivot member on opposite sides of its pivot point, said tapes each being operable to move one end of said pivoted member towards said rigid member and to then tilt said rigid member from its horizontal position.
